United States Patent

Des. 238,504

Patented Jan. 20, 1976

238,504

BASE

Amnon Michaeli, 135-03 73rd Terrace,
Kew Gardens Hills, N.Y. 11415

Filed Sept. 16, 1974, Ser. No. 506,409

Term of patent 14 years

Int. Cl. D26—05

U.S. Cl. D48—20 J

FIG. 1

FIG. 3

FIG. 2

FIG. 1 is a top plan view of a base, showing my new design;

FIG. 2 is a typical side elevational view thereof; and

FIG. 3 is an enlarged fragmentary cross-sectional view taken on line 3—3 of FIG. 1.

I claim:

The ornamental design for a base, substantially as shown and described.
